UNITED STATES PATENT OFFICE

MAURICE G. KLEMME, OF BELLEVILLE, ILLINOIS, ASSIGNOR TO EAGLE FOUNDRY COMPANY, OF BELLEVILLE, ILLINOIS, A CORPORATION OF ILLINOIS

DESIGN FOR A COOKING STOVE

Application filed February 18, 1933. Serial No. 47,253. Term of patent 3½ years.

To all whom it may concern:

Be it known that I, MAURICE G. KLEMME, a citizen of the United States, and a resident of the city of Belleville, in the county of St. Clair and State of Illinois, have invented a new, original, and ornamental Design for Cooking Stove, of which the following is a specification.

In the accompanying drawing, which forms part of this specification,

Fig. 1 is a perspective view of a cooking stove embodying my invention; and

Fig. 2 is a similar view of said stove with the oven drawer thereof shown in opened position.

I claim:

The ornamental design for a cooking stove, as shown.

MAURICE G. KLEMME.
